MERCHANDISE DISPLAY STAND

Clarence G. Gephardt, Bethesda, Md., and Sidney Danneman, Washington, D.C.

Application October 12, 1956, Serial No. 43,339

Term of patent 3½ years

(Cl. D80—9)

Fig. 1 is a front elevational view of a merchandise display stand, showing our new design;

Fig. 2 is a side elevational view thereof on a reduced scale; and

Fig. 3 is a top plan view of Fig. 1 on a reduced scale. The rear of the merchandise display stand is substantially the same as the front thereof which is shown in the drawing.

We claim:

The ornamental design for a merchandise display stand, as shown and described.
